UNITED STATES PATENT OFFICE.

SELMER A. CLEMETSON AND OLUF H. RASMUSSEN, OF IRON MOUNTAIN, MICHIGAN.

ELECTRIC-LAMP LOCK.

Application filed May 21, 1927. Serial No. 193,331.

The invention relates to electric fixtures and more particularly to lamp bulbs and their sockets, and provides locking means to prevent unauthorized removal of the lamps 5 from the sockets, either for appropriation, or to admit of plugging into the sockets of electric devices, such as curling irons, heaters, and other electric appliances.

The invention provides locking means 10 which may be applied to lamp sockets and bases of ordinary construction, and which admits of the standard lamps being fitted to a socket to which the locking device has been applied, as well as to admit of a lamp 15 provided with the locking device being used in connection with a standard socket.

While the drawing illustrates a preferred embodiment of the invention, it is to be understood that in adapting the means to 20 meet specific needs and requirements the design may be varied and such other changes in the minor details of construction may be resorted to within the scope of the invention as claimed, without departing from the 25 spirit thereof.

For a full understanding of the invention and the merits thereof, reference is to be had to the following description and the drawing hereto attached, in which,—

30 Figure 1 is a side view of an electric lamp socket and base portion of a lamp bulb, provided with locking means embodying the invention, parts being broken away to show more clearly the relationship of the 35 cooperating elements.

Figure 2 is a perspective view of an electric lamp bulb, provided with a complementary part of the locking means.

Figure 3 is a detail sectional view on the 40 line 3—3 of Figure 1.

Figure 4 is a detail perspective view of the base of an electric lamp bulb.

Figure 5 is a plan view of a ratchet ring 45 which is adapted to be fitted to the base of a lamp.

Figure 6 is a detail perspective view of the lock member showing the operating key associated therewith.

Figure 7 is a fragmentary sectional view 50 on the line 7—7 of Figure 1, looking in the direction of the arrows.

Corresponding and like parts are referred to in the following description and designated in the several views of the drawings 55 by like reference characters.

The numeral 1 designates the usual socket

forming an outlet of a wiring system through which current is supplied to a structure for lighting or other purposes. The numeral 2 designates the insulating 60 body disposed within the shell of the socket, and 3 represents the threaded collar which is held to the body 2 by means of screws 4. The collar 3 is adapted to receive the usual threaded base 5 of a lamp 6, or analogous 65 part adapted to be fitted to the socket.

In accordance with the invention a lock member 7 is disposed within the threaded collar 3 and is retained in place by means of the screw 4. The lock member 7 consists 70 of a flat split ring of spring material, such as tempered steel. This ring is notched upon its inner edge at diametrically opposite points, as indicated at 8, to receive the screws 4.

One end of the spring locking ring is curved outwardly, as indicated at 9, to provide a tooth for engagement with one of a series of teeth 10 provided upon the end of the lamp base 5. Oblong washers 11 are 80 mounted upon the headed ends of the screws 4, and are confined between the heads of the screws and the spring locking ring 7 and bridge the notches 8, so as to brace and reinforce the lock member and prevent fracture 85 thereof at the point weakened by the notches 8. A key barrel or guide 12 projects laterally from the shell of the socket about in the plane of the lock member 7 and is adapted to receive a proper key 13 which is 90 formed with a longitudinally disposed bit 14 to engage the toothed end 9 of the lock member and effect disengagement thereof from the toothed portion 10 of the lamp base 5.

The base 5 is adapted to be provided with ratchet teeth 10 in any determinate way and in the case of lamps already marketed or constructed the teeth may form part of a ring 15 which may be soldered or otherwise 100 attached to the end of the base 5. The attaching face of the ring 15 is made concave, as shown most clearly in Figure 1, to conform to the convex surface of the base 5, the toothed face of the ring being flat to conform to the inner wall or flange of the collar 3.

It will be understood from the foregoing that the invention is adapted to be readily applied to standard sockets and lamp bases 110 and the arrangement is such that any standard lamp provided with the usual base may

be applied to a socket to which the lock member 7 has been fitted. It is further observed that a lamp having its base provided with teeth 10 may be successfully used 5 in any standard socket with, or without, the lock member 7. When a socket and lamp provided with the invention are connected substantially as indicated in Figure 1, unauthorized removal of the lamp is prevented, thereby guarding against theft of 10 the lamp, or its removal and the use of electric current without proper compensation. When the lamp is in position the tooth 9 of the lock member 7 engages a tooth of the 15 lamp 8, thereby preventing removal of the lamp from the socket. A person possessing a proper key may introduce the same into the socket through the barrel or guide 12, thereby bringing the bit 14 in engagement 20 with the toothed end of the lock member, whereby rotation of the key depresses the toothed end 9 and disengages the same from the toothed portion 10 of the lamp which may be removed from the socket in the usual 25 way.

Having thus described the invention, we claim:

1. The combination with a lamp socket including the usual shell, the insulating 30 body therein, a threaded collar and screws connecting the threaded collar to the body, of a flat split ring lock member placed against the bottom of the said collar and having portions cut away at diametrically 35 opposite points to receive the said screws,

and oblong washers mounted upon the headed ends of the screws and confined between the heads of the screws and the said lock member and serving to reinforce the latter at the cut away portions receiving the said 40 screws.

2. The combination with a lamp socket including the usual shell, the insulating body therein, a threaded collar and screws connecting the threaded collar to the body, 45 of a lock member placed against the bottom of the said collar and having portions cut away to receive the said screws, and oblong washers mounted upon the headed ends of the screws and confined between the heads 50 of the screws and the said lock member and serving to reinforce the latter at the cut away portions receiving the said screws, a key barrel or guide projecting laterally 55 from the shell of the socket and a lamp base having its end toothed and adapted to be engaged by the said lock member.

3. The combination with a lamp socket and a lamp base, of a lock member secured within the socket and comprising a split 60 flat spring ring having a turned up end portion adjacent the split to provide a tooth and a toothed ring fitted to the end of the lamp base, and having the face adjacent the base concave to conform to the convex out line of the base.

In testimony whereof we affix our signatures.

SELMER A. CLEMETSON. [L. S.]
OLUF H. RASMUSSEN. [L. S.]
